UNITED STATES PATENT OFFICE

GEORGE WALKER, OF BROOKLYN, NEW YORK, ASSIGNOR TO THE JACOBS BROTHERS CO.,
INC., OF BROOKLYN, NEW YORK, A CORPORATION OF NEW YORK

SCALE

Application filed November 14, 1927. Serial No. 233,053.

This invention relates to a scale of the over-and under-weight type.

It is an object of the invention to provide a device of this character, the parts of which will be relatively few in number and individually simple and rugged in construction, these parts being assembled to furnish a scale operating satisfactorily over long periods of time with freedom from mechanical difficulty.

It is a further object of the invention to furnish a scale which may be disposed upon, for example, a counter and in which the registration may be conveniently viewed.

With these and further objects in mind reference is had to the attached sheet of drawings illustrating one practical embodiment of the invention and in which:

Figure 1 is a perspective view of the mechanism employed to connect the beam with the registering mechanism.

Fig. 2 is an enlarged, partly sectional transverse view of the scale, certain of the parts being broken away to disclose underlying construction, and

Fig. 3 is a fragmentary, partly sectional side view of the scale parts as shown in Fig. 2.

It will be noted that the scale, as to the details of its pans or scoops, its dial, end of the pointer, dash-pot, etc., has not been illustrated. Obviously, these several parts may embrace any desired construction and except insofar as they are necessary to a complete scale, form no part of the present invention.

Thus, in these drawings the numeral 10 indicates a base from which a standard 11 extends upwardly, this standard supporting, on its under side, a post 12 which may carry the ends of a check rod assembly 13. Mounted upon the standard is a yoke 14, the arms of which support pivot blocks 15. Bearing upon these blocks are the pivots or knife edge members 16 of the scale beam 17, it being observed that the latter preferably has a central portion in the form of a collar 18.

Mounted upon the standard and extending within the space defined by the collar 18 is a housing 19 of any desired configuration

which, at its upper end, may support a suitably displayed, graduated dial which, in conjunction with a pointer end, provides a registering mechanism (the latter structures not having been shown). 55

In the embodiment illustrated the housing has an inwardly extending block 20 to which a bracket is secured in any desirable manner. This bracket conveniently embraces a base 21 and an arm 22, the latter being bent to extend, as at 23, substantially parallel to the base 21. It will here be observed that the upper edge of the bracket base 21 is preferably straight and that the block 20 has a ledge 24 which bears against this edge so that an operator may readily apply the bracket to extend properly with respect to the housing. The base 21 and inwardly extending portion 23 of the bracket provide bearings for a shaft 25, the latter mounting a pinion 27 and the lower end of a pointer 26. The teeth of this pinion are engaged by a rack 28, the lower end of which is secured to the scale beam. With a view to assuring constant engagement between the teeth of the rack and the pinion, a spring 29 is preferably employed which has one of its ends secured to a post 30, its opposite end being attached to the rack, it being here noted that these parts, when properly set up, are so arranged that this spring, in the embodiment illustrated, will extend at right angles to the rack body when the pointer is in its neutral position. It will furthermore be noted that the connection employed between the rack and the beam is preferably as follows: 75

A bracket 31 is secured to the beam and terminates in a pair of ears 32 between which the lower end of the rack is pivotally supported by means of a pin 33. The end of this pin is bent to extend at right angles to the body thereof and seats in an under-cut notch 34 forming a part of a central extension 35 of the bracket 31. Consequently, the pin cannot be accidentally loosened, but if it becomes necessary to detach the rack member, this may be achieved readily by simply springing the pin end from within the notch and then withdrawing the pin body from between the ears 32. 95

Mounted at the upper end of the standard is a supporting and clamping assembly 36 which adjustably secures the inner end of a spring flexion strip 37 in place. The outer 5 end of this strip extends between a pair of arms 38 forming a part of the scale beam and is slidably engaged by a pair of opposed set screws 39 mounted one by each of the arms 38 and preferably having their inner ends 10 reduced in order that undue friction between the parts may be avoided. Obviously, a scale of this nature may be constructed and assembled readily and when so assembled the parts may be adjusted in order that the 15 registering mechanism will indicate what might be termed a zero condition when the scale parts are in neutral position, this registering mechanism indicating, accurately, over- and under-weight according to whether 20 the scale parts are deflected to a point short of, or beyond their neutral position. With the parts thus adjusted it will be patent that the scale may be employed in connection with any desired weighing problems and that its 25 parts will normally tend to assume a neutral position incident, primarily, to the flexion strip 37 and, secondly, to the manner of mounting of the spring 29. It will be observed, in this connection, that the arm 22 30 of the bracket serves as a guide for the rack during the sliding movements of the latter. It will also be understood that the dashpot (not shown) may be associated with the beam or other desirable parts of the scale in order 35 to dampen the movements of the mechanism when in use.

Thus, among others, the several objects specifically aforementioned are accomplished, but it will be understood that numerous 40 changes in construction and rearrangement of the parts might be resorted to without departing from the spirit of the invention as defined by the claims.

Having described my invention, what I 45 claim as new and desire to secure by Letters Patent is:—

1. A scale including a rockingly mounted beam, a rack connected to move therewith and extending vertically therefrom, a pinion 50 meshing with the teeth of said rack, a bracket, a shaft mounting said pinion and associated with said bracket, a registering mechanism part also secured to said shaft and a guide for said rack and forming a part of said bracket.

2. A scale including a rockingly mounted beam, a rack connected to move therewith and extending vertically therefrom, a pinion meshing with the teeth of said rack, a spring 60 having one of its ends connected to said rack, means fixedly mounting the opposite end of said spring to retain the teeth of the rack in engagement with said pinion and a pointer connected to said pinion.

3. A scale including a rockingly mounted

beam, a rack connected to move therewith and extending vertically therefrom, a pinion meshing with the teeth of said rack, a spring having one of its ends connected to said rack, means fixedly mounting the opposite end of 70 said spring to retain the teeth of the rack in engagement with said pinion and a pointer connected to said pinion, said spring extending to act in a direction substantially at right angles to the direction of movement of said 75 rack when said pointer is in neutral position.

4. A scale including a rockingly mounted beam, a registering mechanism, a bracket presenting a substantially straight edge, 80 means connecting said mechanism with said beam, a housing supporting said bracket and a ledge associated with said housing and bearing against the bracket edge to indicate the proper disposition of the parts with respect to each other.

5. A scale including a rockingly mounted beam, a registering mechanism and means connecting said mechanism with said beam and including a bracket, a connecting member, a pivot pin securing said bracket to said member, said bracket being formed with a notch, the end of said pivot pin being disposed to be sprung into said notch, whereby 90 to releasably retain said pin.

6. A scale including, in combination, a 95 rockingly mounted beam, a registering mechanism movable in a plane substantially transverse to the movements of said beam, means connecting said beam with said registering mechanism and a flexion strip cooperating 100 with said beam to normally retain the same in predetermined position.

7. A scale including, in combination, a rockingly mounted beam, a registering mechanism, a substantially horizontally extending 105 flexion strip, means fixedly mounting one of the ends of said strip, means connecting the opposite end thereof to said beam, means including a rack and pinion connecting said registering mechanism to said beam, and a 110 spring disposed to act in a direction substantially at right angles to the direction of travel of the rack when the latter, the registering mechanism and said beam are in neutral positions.

8. A scale including a beam, means for rockingly mounting the same at a substantially central point, a registering mechanism including a pointer to move relatively to a dial, the movements of such latter elements being in a plane transverse to the movements of said beam, means connecting said beam to said registering mechanism and the connection between said means and the beam being adjacent the point of mounting of the latter.

9. A scale including a beam, means for rockingly mounting the same at a substantially central point, a registering mechanism including a pointer to move relatively to a dial, the movements of such latter elements

being in a plane transverse to the movements of said beam, said registering mechanism extending above said beam at a point substantially in line with its point of mounting and 5 means connecting said beam to said registering mechanism and extending to one side of said point of mounting.

10. A scale including a beam, means for 10 substantially central point, a registering mechanism including a pointer to move relatively to a dial, the movements of such latter elements being in a plane transverse to the movements of said beam, means connecting said beam to 15 said registering mechanism, and means forming a part of said scale and tending normally to maintain said beam and mechanism in neutral positions.

11. A scale including a beam, means for 20 substantially central point, a registering mechanism including a pointer to move relatively to a dial, the movements of such latter elements being in a plane transverse to the movements 25 of said beam, means connecting said beam to said registering mechanism, and resilient means associated with said scale and connected to the parts thereof to offer increasing resistance to deflections of the beam and registering mechanism to positions beyond neutral.

12. A scale including, in combination, a beam, a rocking mounting for the same substantially intermediate its ends, a registering 35 mechanism including a pointer movable with respect to a dial and the parts of said mechanism being disposed to have their movements in a plane substantially transverse to the plane of movement of said beam, means for 40 actuating said registering mechanism to have a range of movement amplified in relation to the movements of the beam and means for connecting said beam to said registering mechanism.

45 13. A scale including a beam, a mounting for said beam disposed substantially intermediate its ends, a registering mechanism including a pointer to move with respect to a dial and said mechanism being disposed to 50 have its movements in a plane substantially transverse of the plane in which said beam moves, a flexion strip connected to said beam to normally maintain the same and said registering mechanisms in neutral positions, and 55 means connecting said beam to said registering mechanism.

14. A scale including a beam, a mounting for said beam disposed substantially intermediate its ends, a registering mechanism including 60 a pointer to move with respect to a dial, said mechanism being disposed to have its movements in a plane substantially transverse of the plane in which said beam moves, a flexion strip connected to said beam to normally maintain the same and said register- 65

ing mechanisms in neutral positions, and means connecting said beam to said registering mechanism, a fixed portion forming a part of said scale, means connecting one of the ends of said strip to said fixed part and means connecting the opposite end of said strip to said beam. 70

15. A scale including a beam, a mounting for said beam disposed substantially intermediate its ends, a registering mechanism including a pointer to move with respect to a dial, said mechanism being disposed to have its movements in a plane substantially transverse of the plane in which said beam moves, a flexion strip connected to said beam to normally maintain the same and said registering mechanisms in neutral positions, means connecting said beam to said registering mechanism, a fixed portion forming a part of said scale, means connecting one of the ends of said strip to said fixed part, means connecting the opposite end of said strip to said beam, one of said connections being rigid and means forming a part of the other of said connections and having sliding contact with the opposite faces of said strip. 80

In testimony whereof I affix my signature.
GEORGE WALKER.
